Primary Examiner — Susan Bennett Hattan*Assistant Examiner* — Elizabeth S Ko(74) *Attorney, Agent, or Firm* — Next IP Law Group LLC(57) **CLAIM**

The ornamental design for a support clip, as shown and described.

DESCRIPTION

FIG. 1 is a perspective view of a support clip;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in FIGS. 1-7 are for the purpose of showing portions of the support clip that form no part of the claimed design.
